I INVENTOR
FRANK H. BROWN
BY *Nigdon & Longair*
ATTY'S.

UNITED STATES PATENT OFFICE.

FRANK H. BROWN, OF ST. LOUIS, MISSOURI.

SPRINGLESS DIAL-SCALE.

No. 835,899.

Specification of Letters Patent.

Patented Nov. 13, 1906.

Application filed January 29, 1906. Serial No. 298,312.

To all whom it may concern:

Be it known that I, FRANK H. BROWN, a citizen of the United States, and a resident of St. Louis, Missouri, have invented certain new and useful Improvements in Springless Dial-Scales, of which the following is a specification containing a full, clear, and exact description, reference being had to the accompanying drawings, forming a part hereof.

My invention relates to a springless dial-scale; and the object of my invention is to provide a dial-scale with mechanism which will instantly return the indicating-finger back to zero after the weighing operation is complete and the load has been removed from the scale-platform.

Heretofore dial-scales have been provided with spring-actuated mechanism for returning the indicating-finger; but springs are more or less unreliable, easily get out of order, and in time become weakened, and I propose to provide a mechanism with a weight which will be elevated when a load is weighed and which will descend when the load is removed from the scale-platform and return the indicating-finger to the zero-mark upon the dial.

To the above purposes my invention consists of certain novel features of construction and arrangement of parts, which will be hereinafter more clearly set forth, pointed out in my claim, and illustrated in the accompanying drawings, in which—

Figure 1 is a perspective view of a scale constructed in accordance with my invention. Fig. 2 is an enlarged vertical section taken on the line 2 2 of Fig. 1. Fig. 3 is a vertical section taken on the line 3 3 of Fig. 2.

Referring by numerals to the accompanying drawings, 1 indicates the scale-platform, 2 the vertically-arranged housing at the rear of the platform, and 3 the dial upon the front side of the upper end of said housing.

Journaled in the center of the dial 3 and in a bearing 4, that is fixed to the inner face of the rear wall of the housing 3, is a horizontally-arranged shaft 5, on the forward end of which is fixed the indicating-finger 6. Mounted on the shaft 5 adjacent the bearing 4 is a pinion 7. Arranged for rotation upon a stub-shaft 8, that extends inwardly from the inside face of the rear wall of the housing 2, is a pinion 9, which meshes with the pinion 7. Journaled in bearings 10, that are fixed to the inside face of one of the side walls of the housing 2, is a shaft 11, upon which is mount-

ed a large gear-wheel 12, with which the pinion 9 meshes. Fixed upon this shaft 11 a short distance from the gear-wheel 12 is a pinion 13, and fixed to and depending from the shaft 11, adjacent said pinion, is an arm 14, on the lower end of which is arranged a weight 15. Arranged to slide vertically through a guide 16, that is fixed to the rear wall of the housing 2, is a rack-bar 17, the teeth of which mesh with the pinion 13. Pivotedly connected to the lower end of this rack-bar is a horizontally-arranged lever 18, which is fulcrumed at its opposite end to a bearing 19, fixed to one of the side walls of the housing 2. Pivotedly connected to the lever 18 adjacent its center is the upper end of a vertically-arranged rod 20, which is connected at its lower end to the weighing mechanism arranged in the base of the scale beneath the platform 1.

The various parts of the mechanism just described are so arranged as that when the weight 15 is at its lowermost position and the arm 14 is vertical the indicating-finger 6 is at the zero-point on the scale of the dial 3. When a load is placed upon the scale-platform 1, the rod 20 is moved downwardly, and as a result the end of the lever 18 to which the lower end of the rack-bar 17 is pivoted is likewise moved downwardly. This movement necessarily rotates the shaft 11 as the teeth of the rack-bar 17 mesh with the pinion 13, and consequently the gear-wheel 12 is rotated in the direction indicated by the arrow in Fig. 2. This rotary motion is transmitted, by means of the pinion 9, to the pinion 7 and shaft 5, and as a result the indicating-finger 6 moves around upon the scale of the dial to indicate the weight of the load upon the scale-platform.

As soon as the load is removed from the platform the weighing mechanism beneath said platform will reassume its normal position and the rod 20 will move upwardly a slight distance. Following this action the weight 15 will swing downwardly to its normal position, bringing the rod 14 into vertical position, and the rack-bar 17, together with the various pinions and gear-wheel, will move in reverse directions to the movements just described, and as a result the indicating-finger 6 will return to the zero-point upon the dial. Dotted lines in Fig. 2 illustrate the swing of the arm 14 and weight 15.

The mechanism herein described operates freely and accurately, and the weight in

swinging to its normal position after having been elevated quickly and positively returns the indicating-finger to the zero-point, and as the various operating parts are geared together there will be no vibration of the indicating-finger after its return to the zero-point, as is the case where springs are made use of. The device is simple, inexpensive, is positive in operation, and can be readily applied to all forms of platform-scales.

I claim:

In a dial-scale, the combination with the indicating-finger of a dial and weighing mechanism, of a train of gearing leading from the shaft on which the indicating-finger is positioned, a shaft mounted for rotation adjacent said train of gearing, a large gear-wheel mounted on said shaft and meshing with one of the pinions of the train of gearing, a pinion

mounted upon the shaft, a vertically-disposed rack engaging the pinion, a bearing through which the upper end of said rack operates, a horizontally-disposed lever fulcrumed at one end and pivotally connected at its outer end to the lower end of the rack and to which lever is connected one of the levers of the weighing mechanism, an arm fixed to and depending from the shaft, and a weight carried by the lower end of said arm; substantially as specified.

In testimony whereof I have signed my name to this specification in presence of two subscribing witnesses.

FRANK H. BROWN.
